DISPENSING MACHINE

Benjamin D. Knox, St. Louis, Mo.

Application April 30, 1938, Serial No. 205,172

10 Claims. (Cl. 101—96)

This invention relates to a coin controlled dispensing or registering machine.

An object of the invention is to provide a machine for dispensing slips, coupons or contracts which will require registration of the recipient for identification before the operation of the device can be completed; and to provide in such a device operating mechanism which is simple in construction and positive in operation.

Specific objects will be apparent from the following detail description taken in connection with the accompanying drawings.

Another object of the invention is to provide coin controlled apparatus for a dispensing or registering machine to cover and uncover a window, which provides access for registration or operation.

Fig. 1 is a plan view of a device embodying my invention;

Fig. 2 is a vertical section (with the casing removed) showing paper roll feed mechanism and ribbon roll mechanism;

Fig. 3 is a vertical section (with the casing removed) showing in particular latch and release mechanism;

Fig. 4 is a side elevation partly in section with the casing removed showing inter alia stamping mechanism;

Fig. 5 is a plan view of the front portion of the machine, with the casing in section; and

Figs. 6, 7 and 8 show details of ribbon rewind mechanism.

The machine, illustrated in the drawings and embodying the invention, has a main operating shaft 1, to which is attached a hand lever 2. A latching disc 3 has a lug 4 engaged by a pawl 5 at the end of a cycle of operation, as best shown in Fig. 3. The pawl 5 is operable to unlatch the mechanism by a coin controlled device, including a slide 6, operatively connected to a push rod 7, which is secured at its outer end to a lever 8, which lever is connected to the pawl 5 by a link 9. A plate 10 is mounted to be moved back and forth to cover and uncover openings 11 and 12 in an apron 13 which forms a part of the casing of the machine. A lever 14 at each side of the machine is connected at its upper end to the plate 10 and at its lower end to a crank 15 secured to the operating shaft 1. The arrangement is such that a counter-clockwise (Figs. 3 and 4) movement of the shaft 1 by the handle 2 moves the plate 10 backwardly or right (same figures) to uncover the slots or openings 11 and 12.

Printing mechanism, operated by the shaft 1 during the aforementioned counter-clockwise

movement of the shaft 1, indicates a plunger 16 mounted in a guide 17 and connected by a link 18 to a bell crank lever 19. The bell crank lever 19 has a hook 20 engageable by a hook 21 on the end of a link 22, which is pivotally connected to a crank 23 secured to the shaft 1. A spring 24 is interposed between the top of the guide 17 and a shoulder 25 near the top of the plunger. The arrangement is such that during the aforementioned counter-clockwise movement of the shaft 10 the link 22 is moved to the left, Fig. 4, rotating the bell-crank lever 19 also in a counter-clockwise direction to a point where the hook 21 is disengaged from the hook 20 permitting the spring 24 to move the plunger 16 upwardly with a strong 10 and uniform force.

The cam 3 has a notch 30 adapted to receive a tooth 31 on the inner end of a pawl or lever 32, which is connected at its outer end to a spring pressed plunger 33. Thus, when the shaft 1 has been moved in a counter-clockwise direction from the position shown in Fig. 3 the notch 30 will register with the tooth 31 and the spring pressed plunger will urge the tooth into the notch, thus latching the shaft 1 against clockwise movement, such being necessary for further operation of the machine.

The plunger 33 has a head 34 positioned beneath the opening 12 and beneath the edge of a strip of paper 35 which is sensitized to receive 30 a fingerprint. In order to move the tooth 31 from the notch 30, the operator must press the head 34, through the opening 12, thereby registering his fingerprint upon the sensitized paper 35.

The paper 35 is carried on a roll 36 supported 35 by a shaft 37, passes through feed rollers 38 and is rerolled on a spool 39 rotated by a shaft 40. Paper 41 is carried by a roll 42 supported by a spindle 43, passes through the feed rollers 38 parallel with the paper 35, over the printing 40 plunger 16, under the opening 11, and through a slot 44, whence it may be detached by the operator.

The feed rollers 38 have gears 45 in mesh one with the other, the lower of which is driven (Fig. 2) through an idler 45a by a gear 46 on a shaft 47 to which is attached a bevel gear 48. A shaft 49 has, at its upper end, a gear 50 meshing with and driving the gear 48 and, at its lower end, a gear 51 meshing with and driven by a bevel gear 50 52.

The reroll shaft 40 is also driven from the gear 52. The shaft 40 has a gear 60 driven by a gear 61 attached to a shaft 62 which also carries a bevel gear 63. A shaft 64 carries at its upper end 55

a gear 65 meshing with and driving the gear 63 and at its lower end carries a gear 66 meshing with and driven by the gear 62. A clutch connection between the gear 62 and the shaft 1 is such that movement in a clockwise direction, Fig. 2 (or counter-clockwise direction Figs. 3 and 4), will be ineffective to move the gear 62; but movement of the shaft 1 in the opposite direction will operate the feed rolls 38 and the reroll 10 shaft 40.

The foregoing describes many of the essential parts of a device embodying the invention as nearly as possible in the order of their operation. A further detailed description of the device and 15 of its operation will assist in understanding the invention of which the machine specifically illustrated in the drawings is an embodiment.

This embodiment includes a base 10, which supports two side frame members 71, spaced and 20 secured by cross bars 72. The frame also includes a face plate 73. The operating shaft 1 is journalled in the frame members 71.

The cam or locking disc 3 (Fig. 3) is rigidly secured to the shaft 1 so that it is effective for 25 holding the shaft against rotation. It includes a shoulder 74 at its periphery in addition to the lug 4 and notch 30. A bracket 75 is secured to a frame member 71 in the path of the shoulder 74 and lug 4, so as to limit the movement of the 30 shaft 1 in both directions.

The pawl 5 has a contractile spring 76 connected in such a manner that the spring holds the pawl against the periphery of the disc 3 until the pawl is moved by the link 9, when it holds 35 the pawl out of engagement and against the lower arm of a stop lever 77 mounted on a pivot 78. Movement of the lever 77 is limited by a stop pin 79. The upper arm of the lever 77 is in the path of the lever 32. The arrangement is such that 40 when the pawl 5 is moved to unlatch the shaft 1, it strikes and rests against the lower arm of the lever 77 until the lever 32 is depressed by the plunger 33, when the lever 32 moves the lever 77 to snap the pawl back in engagement with the 45 periphery of the disc 3.

Coin controlled mechanism including the slide 6 is not shown in detail since per se it is no part 50 of this invention. It may be of any selected construction, for example, that illustrated and described in Letters Patent No. 1,908,752 to Louis M. Hall. It is so arranged that a coin of proper size must be inserted in an aperture 80 in the slide 6, in order to permit the slide to be moved to the 55 extreme rear a sufficient distance to move the rod 7.

The connection between the slide 6 and the rod 7 is made by a lug 81 secured to and moving with the slide 6. The lug 81 is bored for sliding engagement with the rod 7 until it strikes a shoulder 82 on the outer end of the rod 7.

The lever 8 is a lever of the first class, fulcrumed on a pivot 83, which is supported by the frame member 71.

A casing 84 for the machine includes an apron 84a, which has slots or openings 11 and 12, and a slot 44. The opening 11 permits access for writing on the paper 41 when uncovered by the plate 10, and the opening 12, uncovered provides access to the plunger head 34 with, however, the paper 35 interposed. The slot 44 is arranged in the path of the paper 41, which is ejected through it, and has a cutting edge 85, by which the operator may sever a recently printed portion of the paper.

15 A shelf 86 is rigidly secured to the two frame

members 71 by screws 87, in a position below the paper 35 and 41 at the slot or opening 11 and thereby serves as a support for the paper when an operator writes through the opening 11. The shelf 86 has an opening 88 into which the plunger 34 extends.

The levers 14 which move the slide 10 are mounted on pivots 89, each supported by a frame member 71.

The printing mechanism includes cooperatively 10 with the plunger 16, an inked ribbon 90, and a series of printing wheels 91. The wheels 91 are rotated to correct position by gears 92 which are driven by a clock shaft 93. The clock mechanism and the printing wheels per se are no part of this 15 invention. Such mechanism in satisfactory form is now available commercially and need not be shown in detail. The paper 35 and 41 is fed between the ribbon and the plunger. Preferably the paper 41 is coated with an impressionable 20 material on its underside in order to impress the printing and writing on the paper 35, or other manifold means may be selected.

A counter, which may or may not be connected to printing wheels is indicated by the reference 94, and has an operating lever 95, which is connected by a link 86 to a crank 97 (Fig. 3) on the shaft 1.

The ribbon 90 is wound on spools 98 and a rewind device actuated by the bell-crank lever 19 (see Figs. 2 and 6). Each spool has a gear 99 in mesh with a gear 99a on a shaft 100. The shaft 100 has a toothed member or gear 101 actuated by a pawl 102. The pawl 102 is mounted on and movable by a lever 103 which is connected (Figs. 6 and 7) with and movable by a lever 104. The lever 104 is mounted on a pivot 105 supported by a frame member 71. The lower end of the lever 104 has a lug 106 positioned and adapted to be engaged by the bell-crank lever 19 (Fig. 2), 40 therefore movement of the bell-crank lever 19 operates the ribbon rewind mechanism.

A cup or receiver 107 is positioned below the slide 6 to receive coins used in operating the 45 slide.

The foregoing describes in detail the construction of a machine embodying my invention as illustrated in the drawings. A description of the 50 operation of the machine will presently be made. The machine in normal condition and at the end of an operation is in the position shown in the several figures. The cycle of operation includes two phases, the first in which the handle 2 is moved from back to front and in which the rock shaft 1 is moved in a counter-clockwise direction, Figs. 3 and 4 (clockwise direction Fig. 2), 55 and a second phase in which the lever 2 and the shaft 1 are moved in the opposite direction from that of the first phase.

At the beginning of a cycle of operation the 60 rock shaft 1 is locked as best shown in Fig. 3. A coin may then be inserted in the aperture 80 of the slide 6 and the slide moved inwardly so that the lug 81, carried by the slide 6, contacts the shoulder 82 on the rod 7 and moves the lever 8 to 65 retract the pawl 5. When the lever 8, through the link 9, moves the pawl 5 from the position shown in Fig. 3, the outer end of the pawl 5 strikes the idling lever 77, moving it backward until it rests against the stop 79, and the spring 70 76 holds the pawl 5 in retracted position. When the pawl 5 is retracted the shaft 1 is free to be moved by the crank 2.

After the unlatching operation just described the machine may be moved through its first 75

phase, the rock shaft 1 moved in the direction shown by an adjacent arrow, Fig. 3, until the notch 30 in the disc 3 registers with the tooth 31 on the lever 32. During this phase the shaft operates, through the cranks 15 and the levers 14, to move the plate 10 from front to back to uncover the openings 11 and 12. During the same phase the cranks 23 are moved to rock the bell-crank lever 19 and operate the plunger 16 to press the paper 35 and 41 against the printing wheels 91. At the same time the bell-crank lever 19, engaging the lug 106 on the lever 104, operates the ribbon rewind mechanism.

The movement of the shaft 1 during the first phase of the cycle is limited by the lug 4 on the disc 3 striking the abutment or bracket 75, in which position the tooth 31 is spring-pressed into the notch 30 of the disc 3. The mechanism is thereby latched until released against further operation.

At the end of the first phase, the operator may write, through the opening 11, on the paper 41, also duplicating on the paper 35. The table 86 provides a support for the paper beneath the opening.

To unlatch the machine for movement during the second phase, the operator presses the plunger head 34 through the opening 12 and against the paper 35. Thereby the operator's fingerprint is impressed upon the margin of the paper 35 which is properly treated to receive and record a fingerprint. Upon downward movement of the plunger 33 the tooth 31 is elevated and the handle 2 may be moved backward to rock the shaft 1 in a clockwise direction, Figs. 3 and 4 (counter-clockwise direction Fig. 2), in order to accomplish the second phase of the operation.

In moving the shaft during the second phase of the operation the shaft 1, through clutch mechanism (Fig. 2), engages the gear 52 to operate the feed rolls 38 and the rewind shaft 40, to rewind the paper 35 on the roll 39 and to eject, through the slot 42, that portion of the paper 41 which has been printed by the wheels 91, so that it may be detached by the operator.

When the plunger 33 is depressed, the lower end of the lever 32 is moved upwardly striking the upper end of the idler lever 77 and moving that lever so that its lower end presses the pawl 5 toward the disc 3. At the end of the second phase of the cycle the shoulder 74 will again rest against the abutment or bracket 75, the pawl 5 will rest against the lug 4 on the disc 3 and the machine will be latched against further operation until such operation is initiated by the insertion of a coin in the slide 6.

It will be clear from the foregoing description that the invention accomplishes its objects and it will be obvious that various changes may be made in the details of construction, within the scope of the appended claims, without departing from the spirit of this invention.

I claim:

1. In a device of the class described, an operating member, a pawl to engage and latch said member, a spring adapted to hold the pawl selectively in engaging and nonengaging position, coin-controlled mechanism to release said pawl, an idling lever, a second latch adapted to hold said operating member and when released to engage said lever and thereby move said pawl to operating position, and a manually operable plunger adapted to underlie a record sheet for operating said second latch.

2. In a device of the class described, means

for advancing a record strip during a phase of a cycle of operation of the device, coin-controlled operating mechanism for completing said cycle, a latch for said mechanism, and a manually operable actuator adapted to underlie an impression sheet for releasing said latch, whereby operation of the actuator will require a fingerprint of the operator upon said sheet. 5

3. In a device of the class described, means for supporting a record sheet and a coupon sheet, 10 coin-controlled operating mechanism for advancing said sheets, a latch for said mechanism, and a manually operable actuator for releasing said latch positioned beneath said record sheet, whereby operation of the actuator will require a 15 fingerprint of the operator upon the record sheet.

4. In a device of the class described, means for supporting a paper roll, operating mechanism, printing mechanism for said paper operable by said operating mechanism during a first phase 20 of a cycle, means for latching the operating mechanism at the close of the cycle, coin-controlled mechanism for releasing said latching means, a second latch operable at the end of the first phase of the operating mechanism, means for 25 advancing said paper operable during a second phase of the cycle by said operating mechanism, and a manually operable actuator adapted to underlie said paper for releasing said second latch.

5. In a device of the class described, means for 30 supporting a paper roll, operating mechanism, printing mechanism for said paper operable by said operating mechanism during a first phase of a cycle, means for latching the operating mechanism at the close of the cycle, coin-controlled 35 mechanism for releasing said latching means, a second latch operable at the end of the first phase of the operating mechanism, means for advancing said paper operable during a second phase of the cycle by said operating mechanism, and a manually operable actuator for releasing said second latch adapted to underlie said paper whereby operation of the actuator will require a 40 fingerprint of the operator upon the paper.

6. In a device of the class described, means for 45 supporting a roll of coupon paper and a roll of manifold record paper, a cover plate having an opening for access to said paper for writing thereon, a slide for uncovering and closing said opening, a main operating rock shaft, connections 50 between the shaft and the slide whereby the slide is moved to uncover the opening during a first phase of a cycle, a latch for securing the shaft at the end of the cycle, coin-controlled mechanism for releasing the latch, paper advancing 55 mechanism connected to said rock shaft and operable during a second phase of the cycle, a second latch securing the shaft at the end of the first phase, and a manually operable actuator for releasing said second latch adapted to underlie 60 the record paper whereby operation of the actuator will require a fingerprint of the operator upon the record paper.

7. In a device of the class described, the combination comprising coin-controlled operating 65 mechanism, a manual control device for said mechanism, a manually operable actuator for said device, and means for guiding an impression sheet over said actuator whereby operation of the actuator will require a fingerprint of the operator 70 upon said sheet.

8. In a device of the class described, the combination comprising coin-controlled operating mechanism, a manual control device for said mechanism, a manually operable actuator for said 75

- device, means for guiding an impression sheet over said actuator whereby operation of the actuator will require a fingerprint of the operator upon said sheet, and means operable by said mechanism for advancing said sheet.
9. In a device of the class described, the combination comprising coin-controlled operating mechanism, a manual control device for said mechanism, a manually operable actuator for said device, means for guiding an impression sheet over said actuator whereby operation of the actuator will require a fingerprint of the operator upon said sheet, and a slide operable by said mechanism for providing access to said actuator.
10. In a device of the class described, the combination comprising coin-controlled operating mechanism, a manual control device for said mechanism, a manually operable actuator for said device, and means for supporting and guiding a pair of superimposed sheets, said means being constructed and arranged in such a manner that the bottom sheet is positioned over said actuator and the top sheet is to one side of the actuator, whereby operation of the actuator will permit and require a fingerprint of the operator upon the bottom sheet.

BENJAMIN D. KNOX.
